(57) **CLAIM**

The ornamental design for an absorbent article package, as shown and described.

DESCRIPTION

The file of this patent contains at least one drawing executed in color. Copies of this patent with color drawings will be provided by the Office upon request and payment of the necessary fee.

FIG. 1 is a perspective front view of an embodiment of an absorbent article package embodying the new design; FIG. 2 is a front view of the design shown in FIG. 1; FIG. 3 is a right side view of the design shown in FIG. 1; FIG. 4 is a back view of the design shown in FIG. 1; FIG. 5 is a left side view of the design shown in FIG. 1; FIG. 6 is a top view of the design shown in FIG. 1; and FIG. 7 is a bottom view of the design shown in FIG. 1. FIG. 8 is a perspective front view of another embodiment of an absorbent article package embodying the new design; FIG. 9 is a front view of the design shown in FIG. 8; FIG. 10 is a right side view of the design shown in FIG. 8; FIG. 11 is a back view of the design shown in FIG. 8; FIG. 12 is a left side view of the design shown in FIG. 8; FIG. 13 is a top view of the design shown in FIG. 8; and FIG. 14 is a bottom view of the design shown in FIG. 8. FIG. 15 is a perspective front view of another embodiment of an absorbent article package embodying the new design; FIG. 16 is a front view of the design shown in FIG. 15; FIG. 17 is a right side view of the design shown in FIG. 15; FIG. 18 is a back view of the design shown in FIG. 15; FIG. 19 is a left side view of the design shown in FIG. 15; FIG. 20 is a top view of the design shown in FIG. 15; and, FIG. 21 is a bottom view of the design shown in FIG. 15. With the exception of the broken lines within the “tags” shown in FIGS. 1, 2, 8, 9 depicting portions of the claimed surface indicia, the broken lines immediately adjacent claimed surfaces depict boundaries that form no part of the claimed design; all other broken lines depict portions of the absorbent article package that form no part of the claimed design.
